SIGNALING APPARATUS FOR TELEPHONE SYSTEMS

Filed June 13, 1921

Fig: 2

— Inventor —
Martin L. Nelson

Chas. W. Candy Atty:

UNITED STATES PATENT OFFICE.

MARTIN L. NELSON, OF CHICAGO, ILLINOIS, ASSIGNOR TO AUTOMATIC ELECTRIC COMPANY, OF CHICAGO, ILLINOIS, A CORPORATION OF ILLINOIS.

SIGNALING APPARATUS FOR TELEPHONE SYSTEMS.

Application filed June 13, 1921. Serial No. 477,266.

To all whom it may concern:

Be it known that I, MARTIN L. NELSON, a citizen of the United States of America, and a resident of Chicago, Cook County, and 5 State of Illinois, have invented certain new and useful Improvements in Signaling Apparatus for Telephone Systems, of which the following is a specification.

This invention relates in general to signaling apparatus for telephone systems, and especially to apparatus of this character which is used for producing audible busy signals and other similar signals in automatic or manual telephone systems. The 10 apparatus herein shown is especially designed for use in automatic telephone systems, but is also adapted for use in manual systems.

The object of the invention is to provide 15 audible signaling equipment of the character designated which will produce clear, uniform and distinct signals, which is economical to manufacture, and which will operate continuously for long periods with a minimum of attention.

The invention will be described with 20 reference to the accompanying drawings, in which Fig. 1 shows a busy signaling machine which is adapted to furnish busy signaling currents of two different volumes, one for use at the connector boards in an automatic telephone system, and the other for use at the trunk boards. Fig. 2 shows a 25 signaling machine which is intended to furnish the characteristic dial tone whereby calling automatic subscribers are notified that they have obtained access to directly controllable automatic switches and that they may, therefore, proceed to operate their calling devices.

Referring to Fig. 1, the signaling machine 30 therein shown is one of two duplicate sets which are ordinarily provided for an exchange. The common leads 2 and 3 supply the signaling current generated by the machine to the connector and trunk switchboards, respectively, and when the switch S² is closed these leads are connected with the signaling machine shown by way of leads 4 and 5. The leads 6 and 7 correspond to the leads 4 and 5 and extend to the other

machine of the set. It will be clear that if the other set is to be used instead of the one which is shown in the drawing, switch S¹ will be closed and switch S² will be 55 opened.

The essential parts of the set shown in Fig. 1 are the buzzer, the magnet coils of which are indicated by the reference character 15; the transformer R; and the relay 60 interrupter comprising relays 20, 21, and 22. The buzzer is provided with an armature 16 which consists of a heavy steel spring, whereby the buzzer is caused to operate at a very high frequency. The 65 transformer R has its primary winding included in a local circuit with the buzzer and the battery, while its secondary winding is in series with the common signaling leads 4 and 5. The relay interrupter is provided 70 in order to produce the characteristic intermittent buzz of the busy tone. When the set is in use the relays energize and de-energize in continuous succession, and relay 20 intermittently short circuits the secondary 75 winding of the transformer R.

In order to have the machine operate with the maximum efficiency it is essential that the various condensers, retard coils, etc., have values which are in correct proportion 80 to each other. The table below gives certain values which have been determined by experiment to be very satisfactory, but it is to be understood that these may be modified if desired, and the invention is, therefore, not 85 limited to the precise figures indicated. The values given are for operation on a forty-eight volt battery.

Buzzer magnet 15	800 ohms.	90
Non-inductive resistance 18	500 "	
Condenser 17	0.4 micro-farads.	
Retardation coil 12	200 ohms.	
Resistance 18	100 "	
Retardation coil 9	50 "	
Condenser 8	2 micro-farads.	
Primary winding 10 of transformer R	54 ohms.	
Secondary " 11 "	3 "	95

The operation is as follows: When the double pole double throw knife switch S³ is closed the battery is connected in bridge of conductors 13 and 14, and a local circuit is completed for the buzzer, which may be 100 traced from the negative pole of the battery by way of the upper switch blade, conductor

13, retardation coil 12, primary winding 10 of the transformer R, conductor 17, winding of the buzzer magnet 15, a section of conductor 14, and through the lower switch 6 blade to the positive pole of the battery. Magnet 15 is energized over the above traced circuit and the buzzer consequently begins to operate, since the armature thereof short circuits the magnet winding every time it is 10 attracted, and by induction between the two transformer windings high frequency current is induced in the secondary winding 11.

At the same time that the local circuit is closed for the buzzer the relay interrupter is 15 set in motion. When the battery is connected across conductors 13 and 14 circuits are closed simultaneously for all three of the relays 20, 21, and 22. Relay 20, having more contact springs to operate than either of 20 the other relays, will not energize quite as quickly as the other two. Relay 21, whose circuit is controlled by relay 20 at armature 25, will completely energize, but relay 22, although it may start to pull up, will immediately fall back as soon as its circuit is 25 opened at armature 26 of relay 21. At the initial closure of the circuit, therefore, relay 21 will become fully energized. An instant later relay 20 will operate, whereupon the 30 circuit of relay 21 is broken at armature 25. Upon deenergizing, relay 21 closes the circuit of relay 22 at armature 26. Upon energizing, relay 22 breaks the circuit of relay 20 at armature 27. Relay 20 now falls back 35 and at armature 25 again closes the circuit of relay 21. These operations, in which the relays are energized alternately, will continue indefinitely, or as long as the circuit remains closed, and it will be seen, therefore, 40 that relay 20 will periodically short circuit the secondary winding 11 of the transformer R at the back contact of its armature 24. This operation periodically stops the generation of signaling current 45 and produces the well known characteristic busy buzz. In actual practice the retardation coil 9 is usually mounted quite close to the transformer R, and in order to prevent the generation of weak signaling current by 50 stray magnetic flux this coil is shorted out also by means of armature 23.

The manner in which the busy signaling currents are applied to a calling subscriber's line in order to give him the required audible 55 signal is well known and need not be described in detail. The conductor 2 is multiplied into all of the connector boards and supplies busy signaling current to notify subscribers that the called lines are busy. 60 It will be observed that the circuit for the common conductor 2 includes the condenser 8 and retardation coil 9. The condenser is included in order to prevent any flow of direct current over the circuit, while the retardation coil 9 is added in order to reduce 65

the volume of the signaling current. The circuit conditions at the connectors are more efficient than they are at the trunk boards and consequently it is necessary to reduce the volume somewhat in order to avoid giving 70 too loud a signal. The common conductor 3 extends to all of the selector boards in the exchange and provides signaling current for giving a calling subscriber a busy signal in case all outgoing trunks of the selected group 75 are busy. The use of busy signaling current for this purpose is described in the U. S. Patent to Jacobsen No. 1,352,605, granted September 14, 1920.

Referring now to Fig. 2, the apparatus 80 shown therein comprises a duplicate set of dial tone machines, which, as before stated, are used for supplying signaling currents for giving the characteristic dial tones to calling subscribers, these dial tones being 85 audible signals which advise the calling subscribers that they may begin to operate their calling devices. The use of signals of this character is described in the patent to Jacobsen above referred to. 90

In view of the explanation of the busy signaling equipment shown in, Fig. 1, it will be unnecessary to go into minute details with regard to the apparatus shown in Fig. 2. The buzzer 52 is substantially like the 95 buzzer 15 except that it is arranged to vibrate with a different frequency in order to generate a different characteristic tone. When the double pole double throw knife switch S^e is closed the buzzer 52 begins to 100 operate. The single pole single throw switch S⁴ may now be closed and a signaling current will be generated in the secondary winding 54 of the transformer R' by inductive action between the said winding and the primary winding 53. The common conductor 50 extends to the first selector boards where it is multiplied to the various switches, as illustrated in the Jacobsen patent above 105 cited. 110

It will be understood that in the case of the dial tone apparatus, both of the duplicate sets which are commonly used are shown in the drawing. The apparatus just described constitutes the first set and is 115 placed in operation by the closure of switches S^e and S⁴ as described, while the apparatus immediately below constitutes the second set and is placed in service by the closure of switches S⁷ and S⁸. 120

It will be observed that in the case of the busy signaling machine of Fig. 1, and also in the case of the dial tone machines, double pole double throw knife switches are used to connect the machines with the battery. Switches of this type are provided in order to permit of an occasional reversal of the battery, whereby too rapid burning away of the contact points on the buzzer is prevented. 125

Having described my invention, what I 130

consider to be new and desire to have protected by Letters Patent will be pointed out in the appended claims.

What I claim as my invention is:

- 5 1. In a signaling system, a common signaling conductor, a transformer having a secondary winding in series with said conductor, a local circuit including a buzzer and a primary winding of said transformer, a series of relays and circuit connections for energizing said relays alternately, and contacts on one of said relays for short circuiting said secondary winding.
- 10 2. In a signaling system, a common signaling conductor, a transformer having a secondary winding in series with said conductor, a local circuit including a magnet and the primary winding of said transformer, an armature for said magnet adapted to short circuit the magnet winding to cause said magnet to operate as a buzzer, a relay interrupter comprising a series of relays, each relay being adapted to open the

circuit of the next relay in the series, and contacts closed periodically by one of said relays for short circuiting the said secondary winding.

- 15 3. In a signaling system, a common signaling conductor having two branches, a retardation coil included in one branch, a transformer having a secondary winding in series with the undivided portion of said conductor, a local circuit including a buzzer and a primary winding of said transformer, a relay interrupter and circuit connections for energizing the relays of said interrupter in continuous succession, contacts actuated periodically by one of said relays for short-circuiting said secondary winding, and other contacts actuated by the same relay at the same time for short circuiting said retardation coil.

In witness whereof, I hereunto subscribe my name this 3rd day of June, A. D., 1921.

MARTIN L. NELSON.
